DESIGN FOR A SUSPENDER

Saul Schiller, New York, N. Y.

Application April 21, 1937, Serial No. 68,908

Term of patent 3½ years

To all whom it may concern:

Be it known that I, Saul Schiller, a citizen of the United States and resident of New York city, in the county of New York and State of New York, have invented a new, original, and ornamental Design for a Suspender, of which the following is a specification, reference being had to the accompanying drawing, forming a part thereof.

Fig. 1 is a face view of a suspender, showing my new design.

Fig. 2 is an enlarged fragmentary view of one end of same.

Fig. 3 is a rear view of Fig. 2.

I claim:

The ornamental design for a suspender, as shown.

SAUL SCHILLER.
